UNITED STATES PATENT OFFICE.

CHARLES R. LUCE, OF NEW YORK, N. Y.

DESIGN FOR A STICK-CANDY WRAPPER.

Application filed January 20, 1928. Serial No. 24,943. Term of patent 14 years.

To all whom it may concern:

Be it known that I, CHARLES R. LUCE, a citizen of the United States, and a resident of New York city, in the county of Kings and State of New York, have invented the new, original, and ornamental Design for a Stick-Candy Wrapper of which the following is a specification.

Reference is had to the accompanying drawing forming part thereof, wherein—

Fig. 1 is a top plan view of a stick candy wrapper showing my new design.

Fig. 2 is a side elevational view thereof.
Fig. 3 is a front elevational view thereof.
I claim:

The ornamental design for a stick candy wrapper substantially as shown.

Signed at Jersey City in the county of Hudson and State of N. J., this 18th day of January, A. D. nineteen hundred and twenty-eight.

CHARLES R. LUCE.
